UNITED STATES PATENT OFFICE

112,368

DESIGN FOR A SOCK

Charles Louis Hynes, Calcutta, India

Application March 17, 1938, Serial No. 75,905
In Great Britain December 3, 1937

Term of patent 3½ years

To all whom it may concern:

Be it known that Charles Louis Hynes, subject of the King of Great Britain, residing at Calcutta, India, has invented a new, original, and ornamental Design for a Sock, of which the following is a specification, reference being had therein to the accompanying drawing, forming part thereof,

The drawing shows a perspective view of a sock embodying my new design.

I claim:

The ornamental design for a sock, as shown.

CHARLES LOUIS HYNES.
